UNITED STATES PATENT OFFICE.

EDWARD H. CHILDS AND CHARLIE R. POWELL, OF BELLAIRE, OHIO.

BLOWN-GLASSWARE MANUFACTURE.

SPECIFICATION forming part of Letters Patent No. 275,999, dated April 17, 1883.

Application filed December 22, 1882. (No model.)

To all whom it may concern:

Be it known that we, EDWARD H. CHILDS and CHARLIE R. POWELL, residents of Bellaire, in the county of Belmont and State of Ohio, have invented certain new and useful Improvements in the Manufacture of Blown Glassware; and we do hereby declare that the following is a full, clear, and exact description of the invention, which will enable others skilled in the art to which it appertains to make and use the same, reference being had to the accompanying drawing, and to letters of reference marked thereon, which forms a part of this specification.

This invention relates to an improved mode of cutting or "cracking off," as it is commonly called, the ends of blown-glass articles—such as tumblers, wine-glasses, and similar articles of glassware—after they have been formed in the mold, preparatory to the finishing operation of polishing or smoothing the edge after being removed from the blow-iron.

Heretofore the blown article has been centered in a suitable cavity in the end of a revolving chuck, with the top end projecting from the edge or face of the chuck a sufficient distance to permit of the end of the article being cut off at the desired length by means of a wire drawn across it at right angles, which scored the glass at the line of contact, and caused it to separate or erase sufficiently to be easily cracked off by the application of moisture to the heated surface of the glass. This mode of "cracking off," as it is known to the trade, is attended with considerable loss from broken ware and gives unsatisfactory results. The upper portion of the article as it comes from the blow-iron is cone-shaped, and is usually much less in length than the portion which is to constitute the finished bowl or tumbler, and the tapering portion, as it nears the apex, is much heavier and stronger. Consequently it cannot be separated readily from the thin shell of the article in the manner it is held in the chuck without danger of injury to the wall of the same during the operation of cracking off the end.

As an improvement on this mode of cracking off the ends of the articles, we propose, first, to reverse the manner of holding the article during the process of cracking off. Instead of securing the bottom end of the article in the

revolving chuck, to place the top end in the cavity and with the aid of a wire or other well-known means to score the article, and by the application of a drop of water to crack it off at the desired length. In this way the severed article falls into the hands of the operator, and the top end either remains in the chuck, to be removed by the workman, or falls out of its own accord.

Second. We further propose, where the articles are of such a nature to demand a different treatment, to substitute for the cutting-wire in common use a revolving chuck, having a suitable recess or cavity in its face adapted to encompass the top end of the article when pushed into it, and, by frictional contact of the interior surface of the chuck with the outer surface of the article, to so heat the same that it can be readily cracked off by the application of moisture in the usual manner.

Third. Our invention further consists of the combination of two chucks, one chuck having a suitable recess or cavity to hold the base of the article firmly in position, and capable of being moved lengthwise of the lathe-bed, and the other chuck arranged to revolve with suitable power, and provided with a recess or cavity adapted to encircle the tapering or top end of the article as it is pushed into it, and by frictional contact so heat the end of the article that it may readily be cracked off by the application of moisture to the heated surface.

The figure is a sectional view of our invention.

The letter A designates the lathe-bed or table, upon which is secured standards B B to support a stationary revolving shaft, C, provided with a pulley, D, for the application of power.

G is a small shaft on a central line with the shaft C, provided with a suitable pulley for the application of power, if needed, and so arranged on standards H H that it is capable of being moved lengthwise of the machine, it being provided with a hand-lever, M, or an equivalent shifting device for that purpose.

E and F are goblet-shaped chucks secured to the end of the shafts C and G. They are made preferably of cast metal, having a cylindrical bore or cavity in the face to receive the end of the article to be cracked off, and the cavities are fitted on the inside with a ring, K,

of cork or an equivalent substance, calculated to give a smooth frictional contact with the surface of the glass article.

N is the article to be operated on.

- 5 The mode of operation is as follows: Power is applied to the chuck E, and the latter made to revolve at a high rate of speed. The article to be cut off is then placed, bottom end first, into the cavity of the chuck F. The operator, by means 10 of his hand or a suitable adjusting-lever, moves the shaft G lengthwise toward the chuck E, thus bringing the two chucks together. The end of the article secured in the chuck F is forced into the cavity of the chuck E until it 15 comes in contact with the edge of the cork ring, which soon heats the glass at the line of contact sufficiently hot to cause it to be readily cracked off by simply wetting the heated end with a drop of water.
- 20 It will be seen that for some articles—such as gas-lamp globes and signal-lights, pitchers, &c.—the chuck F is not adapted to hold them, and they must be held by the hand of the operator; but for light articles, where it is intended 25 to crack them off by frictional contact with the revolving chuck E, it greatly facilitates the operation by holding the article steady, and thus insuring a clear smooth fracture without liability of breakage. The pressure 30 of the chucks on both ends of the article is about equal, and consequently there is not the same liability of breakage as where the thinnest portion of the article is held rigid while the heavier or thicker portion is being broken 35 off, as heretofore practiced.
- 35 The cork lining is a very important adjunct to the revolving chuck, the advantage being that the cork does not darken the glass at the line of contact, as is the case when a wire is 40 used to score the articles, necessitating the

grinding back of the edge in order to remove the discoloration. Other materials may be found that will accomplish the same result; therefore we do not wish to confine ourselves solely to the use of cork for this purpose.

45 In some cases it may be desirable to revolve both chucks, turning them in different directions, and for this purpose we have shown a pulley on the shaft G for the application of power.

50 Having described our invention, what we claim, and desire to secure by Letters Patent of the United States, is—

1. The process of cracking off the ends of blown glassware, which consists in rotating 55 the end of the article within a hollow stationary chuck, by frictional contact with which it is heated.

2. The combination of a stationary chuck adapted to hold the end of the article to be 60 operated on, and capable of lengthwise adjustment, and a revolving chuck having a suitably-shaped cavity in its face and a cork bushing to encompass the end of the article, and by frictional contact so heat the same that the 65 end can readily be cracked off, substantially as herein shown.

3. The combination, with a revolving chuck having a cavity to receive the glass article, of a stationary chuck for holding said article in 70 contact with the revolving chuck, substantially as and for the purpose set forth.

In testimony that we do claim the foregoing as our own we hereby affix our signatures in presence of two witnesses.

EDWARD H. CHILDS.
CHARLIE R. POWELL.
